United States Patent Office

Des. 196,933
Patented Nov. 19, 1963

196,933

NECKLACE OR SIMILAR ARTICLE

Juliette Belin, 188 E. 34th St., Brooklyn, N.Y.

Filed Mar. 5, 1962, Ser. No. 69,071

Term of patent 3½ years

(Cl. D45—16)

Fig. 1

Fig. 2

Fig. 3

FIG. 1 is a front elevational view of a necklace, showing my new design.

FIG. 2 is a cross-sectional view of one of the beads of the necklace, taken on line 2—2 of FIG. 1; and

FIG. 3 is another cross-sectional view, taken on line 3—3 of FIG. 1.

I claim:

The ornamental design for a design for necklace or similar article, as shown.
